UNITED STATES PATENT OFFICE.

CLARENCE W. HOBBS, OF WORCESTER, MASSACHUSETTS, ASSIGNOR TO
HOBBS MANUFACTURING COMPANY, OF SAME PLACE.

MACHINE FOR CUTTING ROUND OR OVAL BLANKS.

SPECIFICATION forming part of Letters Patent No. 670,636, dated March 26, 1901.

Application filed April 9, 1898. Serial No. 676,997. (No model.)

To all whom it may concern:

Be it known that I, CLARENCE W. HOBBS, a citizen of the United States, residing at Worcester, in the county of Worcester and 5 State of Massachusetts, have invented a new and useful Improvement in Machines for Cutting Round or Oval Blanks for Paper Boxes, of which the following is a specification, accompanied by drawings forming a part of the 10 same.

The object of my invention is to provide a machine by which blanks can be cut from sheets of cardboard either round, oval, or elliptical designed for the covers or bottoms of 15 paper boxes which are round, oval, or elliptical in shape; and it consists in the construction and arrangement of parts, as hereinafter described, and set forth in the annexed claims.

Figure 1 of the drawings represents a side 20 elevation of a machine embodying my invention for cutting round, oval, or elliptical blanks for paper boxes. Fig. 2 is a plan view of the machine with the adjustable frame F for holding the cardboard removed. Fig. 3 is 25 a plan view of the sliding table D, representing the same in proper position for cutting an oval blank from a sheet of cardboard. Fig. 4 is a side view of my improved machine with the clamping-plates raised in order to disconnect the adjustable frame F from the sliding 30 table. Fig. 5 is a top view of the sliding table D, held in position to cut an elliptical blank from a sheet of cardboard. Fig. 6 is a top view of the sliding table D with the slotted disk J removed. Fig. 7 is a view of the 35 under side of the slotted disk J. Fig. 8 is a sectional view of the sliding table D on line 8 8, Fig. 6. Fig. 9 is a vertical central sectional view of the stud adjustably held in the 40 transverse slot of the sliding table, and Fig. 10 is a vertical central sectional view of the stud held in a fixed position in the sliding table D.

Similar letters refer to similar parts in the 45 different figures.

Referring to the drawings, A denotes the bed of the machine, upon which the operative parts are supported.

A' denotes an upright stand supported upon 50 one end of the bed A and containing the journal-bearings for a pair of shafts B B', located

one above the other in the same vertical plane and carrying the rotary cutters B² B³. The shafts B B' are connected by gears B⁴ B⁵ and are rotated by a crank B⁶, attached to the 55 lower shaft B'. The bed A is provided with ways A² on its upper surface and a central longitudinal slot A³. Resting upon the bed A is a plate C, capable of sliding lengthwise the bed on the ways A² and of being clamped 60 in position by a screw C', engaging a nut C², bearing against the under side of the bed and having a lever-handle C³. The plate C is provided with a way C⁴, extending transversely across the plate C and serving as a guide for 65 a sliding table D, which is provided with a slot D', inclosing the bolt C', by which the sliding table D is clamped in position on the plate C.

Supported upon the bed A and capable of 70 sliding thereon on the ways A² is a stand E, provided with a foot E', which rests upon the upper surface of the bed. Screwed into the upper end of the stand E is a bolt E², which forms a pintle upon which the U-shaped 75 frame F is hinged. The frame F carries in each of its arms F' F² the spindles F³ F⁴, having their axes in alinement and carrying the clamping-plates F⁶ F⁶, between which a sheet of cardboard G is clamped. 80

The spindles F³ F⁴ when the sheet of cardboard is clamped between them are capable of being rotated about a common axis, thereby rotating the sheet of cardboard G against the cutting edges of the rotary cutters B² B³. 85 The table D is provided with a boss D², having a projecting stud D³, which fits a corresponding recess (not shown) in the lower end of the spindle F⁴, thereby forming the center upon which the spindle is rotated by means 90 of a hand-wheel F⁷.

In order to cut a round blank from the sheet of cardboard, the sliding table D is moved on the plate C transversely to the bed A until the stud D³ is brought into the center of the bed or in the same vertical plane as the axes of the rotating cutters B² B³. The plate C is also moved longitudinally on the bed A until the center of the stud D³ is brought the proper distance from the vertical plane of the cutters B² B³ to produce a 95 round piece of cardboard of the required diameter. 100

ameter, and the plate C and sliding table D are then clamped to the bed by means of the nut C², bolt C', and hand-lever C³. The stand E is moved along on the bed A in order to bring the axes of the spindles F³ F⁴ directly over the center of the stud D³, and the spindle F⁴ is then lowered upon the stud D³, as represented in Fig. 1. A sheet of cardboard G is placed between the clamping-plates F⁵ F⁶, and the upper clamping-plate F⁵ is pressed against the cardboard by raising the bent lever H and curved link H', which has a swiveled connection with the upper end of the spindle F³ to allow the spindle F³ to rotate. The rotation of the spindles F⁴ and F³ by means of the hand-wheel F⁷ causes the cardboard G, held between the clamping-plates F⁵ F⁶, to be rotated against the cutting edges of the cutters B² B³, thereby trimming the edge of the cardboard into a blank of circular form whose radius is equal to the distance between the cutting edges of the cutters B² B³ and the axes of the spindles F³ F⁴.

Placed upon the upper surface of the sliding table D is an oval-shaped frame I, held between a rib I' and a pin I², projecting from the upper surface of the table. The frame I is provided with two holes I³ I³ in its opposite sides, which are adapted to receive a pair of studs F⁸ F⁸, which project from the lower side of the hand-wheel F⁷. In order to cut an oval form, the sliding plate D is moved transversely on the plate C in order to bring the pin I² over the center of the bed or in the same vertical plane as the axes of the rotating cutters B² B³, and the plate C is adjusted longitudinally on the bed A to bring the oval frame the proper distance from the rotating cutters. The spindle F⁴ is then raised off the stud D³, as represented in Fig. 4, and the studs F⁸ F⁸ are placed in the holes I³ I³, the longitudinal movement of the stand E along the bed A and the swinging movement of the frame F on the pintle E² allowing this to be done. The sheet of cardboard is then clamped between the plates F⁵ F⁶ by the action of the lever H, as above described, and is rotated by means of the hand-wheel F⁷, causing the frame I to be moved between the rib I' and pin I², thereby carrying the axes of the spindles F³ F⁴ away from and toward the cutters B² B³, as determined by the shape of the frame I, and causing the sheet of cardboard to be cut into an oval form, its major and minor axes having the same proportion as the major and minor axes of the oval frame I. The size of the oval is determined, however, by the distance of the plate C from the vertical plane of the rotating cutters B² B³. As the spindle F⁴ is turned in the operation of cutting an oval blank the stand E slides back and forth on the bed A and the frame F swings about the pintle E² to permit the distance between the axes of the spindles F³ F⁴ and the cutting edges of the cutters B² B³ to vary. If it is desired to change the proportion between the major and minor axes of the blank, it is ac-

complished by replacing the oval frame I by one having different proportions.

In order to cut an elliptical blank from a sheet of cardboard, the studs F⁸ F⁸ upon the hand-wheel F⁷ are placed in the holes J' in a disk J, which rests upon the upper surface of the sliding table D and is provided on its under side with two T-shaped slots J² J³, extending diametrically across the under side of the disk J and at right angles to each other. One of the T-shaped slots incloses the head of a stud K, which is held in a fixed position in the table D, and the other of the T-shaped slots incloses the head of a stud K', which is adjustably held in a T-shaped slot L, extending across the sliding table D. In order to cut an elliptical blank of a predetermined size, the sliding table D is moved along on the plate C to bring the disk J opposite the center of the rotating cutters B² B³, as shown in Figs. 5 and 6, and the plate C is adjustably attached to the bed A at the proper distance from the rotating cutters B² B³ to secure the required diameter of the blank. The sheet of cardboard is clamped between the plates F⁵ F⁶ and is rotated by the hand-wheel F⁷, with the studs F⁸ F⁸ inserted in the holes J' of the disk J, causing the disk J to rotate with the spindle; but the disk J is held upon the two studs K and K', working in the right-angled slots J² J³. The motion of the disk J will be an eccentric motion—that is, the distance of the center of disk J from the vertical plane containing the cutting edges of the cutters B² B³ will vary, so that the curved line cut around the cardboard as it is rotated will be an ellipse, producing an elliptical blank.

What I claim as my invention, and desire to secure by Letters Patent, is—

1. In a machine of the class described, the combination with a cutting mechanism, of a clamping mechanism comprising a pair of clamping-plates capable of rotation about a common axis and means for compressing said plates against a piece of cardboard placed between them, a swinging frame hinged upon a sliding stand and carrying said clamping mechanism, a sliding stand capable of sliding toward or away from said cutting mechanism and means for imparting a predetermined sliding movement to said stand, substantially as described.

2. The combination of a cutting mechanism, a clamping mechanism for clamping a sheet of cardboard, and capable of rotation about an axis at right angles with the sheet of cardboard, a swinging frame carrying said clamping mechanism and hinged to a sliding stand, a sliding stand carrying said swinging frame and capable of sliding toward or away from said cutting mechanism, and means for moving said swinging frame during the rotation of said clamping mechanism, whereby the axis of said clamping mechanism is moved in a predetermined path, substantially as described.

3. In a machine of the class described, the

combination of a cutting mechanism, a clamping mechanism for holding a sheet of cardboard and capable of rotation about an axis at right angles with the sheet of cardboard, 5 a plurality of actuating mechanisms for moving the axis of said clamping mechanism in different paths during its rotation, and means whereby said clamping mechanism is shifted from one actuating mechanism to another, 10 substantially as described.

4. In a machine of the class described, the combination of a bed, a cutting mechanism mounted on said bed, a plate longitudinally adjustable on said bed, a table transversely 15 adjustable on said plate, a stand longitudinally movable on said bed, a frame hinged to said stand, a clamping mechanism journaled in said frame, and means for varying the axis of the clamping mechanism mounted 20 on said table, substantially as described.

5. The combination of a bed A, a stand A' mounted on said bed, a pair of parallel shafts journaled in said stand, rotating cutters car-

ried on said shafts, a swinging frame capable of adjustment either toward or away from 25 said rotating cutters, spindles journaled in said frame having coincident axes, clamping-plates carried by said spindles, means for pressing said plates against a sheet of cardboard placed between them, means for rotating 30 said plates and means for changing the position of said spindles during their rotation, substantially as described.

6. In a machine of the class described, the combination of a cutting mechanism, a rotating spindle, clamping mechanism rotated by 35 said spindle, a hand-wheel attached to said spindle, spurs projecting from said hand-wheel, a plate capable of moving in a predetermined path and provided with holes to receive 40 said spurs, substantially as described.

Dated this 14th day of March, 1898.
CLARENCE W. HOBBS.
